US00D894188S

(12) **United States Design Patent** (10) **Patent No.:** **US D894,188 S**
(45) **Date of Patent:** **** Aug. 25, 2020**

(54) **SIGNAL BOOSTER CASE**

(71) Applicant: **Wilson Electronics, LLC**, St. George, UT (US)

(72) Inventors: **Aaron Jay Hamilton**, Royce City, TX (US); **Scot Herbst**, Santa Cruz, CA (US); **Will Hunter**, Denver, CO (US); **Ellen Posch**, Cleveland Heights, OH (US); **Brooks Stephen Ruhman**, Dallas, TX (US)

(73) Assignee: **Wilson Electronics, LLC**, St. George, UT (US)

(**) Term: **15 Years**

(21) Appl. No.: **29/686,190**

(22) Filed: **Apr. 2, 2019**

(51) LOC (12) Cl. **14-02**

(52) U.S. Cl.

USPC **D14/420**

(58) **Field of Classification Search**

(57) **CLAIM**

The ornamental design for a signal booster case, as shown and described.

DESCRIPTION

FIG. 1 is a top perspective view of the presently claimed design.

FIG. 2 is a side view of the presently claimed design.

FIG. 3 is an opposite side view of the presently claimed design.

FIG. 4 is a front view of the presently claimed design.

FIG. 5 is a rear view of the presently claimed design.

FIG. 6 is a top view of the presently claimed design; and,

FIG. 7 is a bottom view of the presently claimed design.

1 Claim, 3 Drawing Sheets

FIG. 1

FIG. 2**FIG. 3****FIG. 4****FIG. 5**

FIG. 6**FIG. 7**
